UNITED STATES PATENT OFFICE.

IRA HERMAN GAITHER, OF ALBERTON, MARYLAND.

ENDLESS TRAVELING CONVEYER.

SPECIFICATION forming part of Letters Patent No. 466,229, dated December 29, 1891.

Application filed June 13, 1891. Serial No. 396,152. (No model.)

To all whom it may concern:

Be it known that I, IRA HERMAN GAITHER, a citizen of the United States of America, residing at Alberton, in the county of Howard 5 and State of Maryland, have invented certain new and useful Improvements in Endless Traveling Conveyers, of which the following is a specification, reference being had therein to the accompanying drawings.

10 My invention relates to certain improvements in endless traveling conveyers; and it consists in the novel combination and arrangement of parts as hereinafter set forth, illustrated by the accompanying drawings, and 15 pointed out in the claims.

In the drawings, Figure 1 is a sectional elevation of my invention as embodied, for instance, in connection with the grain-carrier of a harvester. Fig. 2 is a plan view thereof, 20 and Fig. 3 a cross-sectional view of the same. Fig. 4 is an enlarged detail perspective view of the conveyer.

In carrying out my invention I construct the conveyers A A, of which one is arranged 25 horizontally and the other vertically, each of plate-sections A' of a length equal to the width of the proposed conveyer and hinged or articulated together at their longitudinal edges, forming substantially an imperforate 30 endless conveyer wholly of plate metal. These conveyers encompass polygonal sprocket-wheels B B, preferably octagonal in their general outline, whose short teeth engage two series of aligning apertures or perforations a 35 in the plate-section A', arranged near the ends of said plate-sections to impel or actuate said conveyers. The sprocket-wheels B are carried by spindles or shafts b, suitably journaled in supports or side pieces c, forming

the horizontal and vertical frame-work of the 40 machine.

The conveyers A are armed or provided at suitable intervals throughout with transverse cleats or slats d to engage the grain, for instance, fed or falling therefrom and prevent 45 its displacement while being conveyed or carried by the conveyers, said slats or cleats also serving to cover the apertures or perforations in the plate-sections to prevent the grain carried upon the conveyers falling therethrough. 50 By this arrangement and construction of parts the employment of rolls as required in connection with the use of the canvas or cloth conveyers and the objectionable sagging attendant upon such use are avoided, while 55 durability is promoted and greater carrying capacity secured, and the use of additional driving chain or link belts is dispensed with, the conveyers herein employed also serving that purpose. 60

Having thus fully described my invention, what I claim as new, and desire to secure by Letters Patent is—

The combination, with the polygonal sprocket-wheels, of the endless conveyer comprising the hinged or articulated plate-sections, having therein series of apertures or perforations near their ends engaged by the short teeth of said wheels, said plate-sections being armed with cleats or slats covering said 65 70 apertures or perforations, substantially as set forth.

In testimony whereof I affix my signature in presence of two witnesses.

IRA HERMAN GAITHER.
